UNITED STATES PATENT OFFICE.

EDGAR C. MATSON, OF HANDLEY, WEST VIRGINIA, ASSIGNOR TO J. A. B. HOLT, OF PRATT, WEST VIRGINIA.

SEWING-MACHINE.

1,379,468.

Specification of Letters Patent.

Patented May 24, 1921.

Application filed February 12, 1920. Serial No. 258,304.

To all whom it may concern:

Be it known that I, EDGAR C. MATSON, a citizen of the United States, residing at Handley, in the county of Kanawha and State of West Virginia, have invented certain new and useful Improvements in Sewing-Machines; and I do declare the following to be a full, clear, and exact description of the invention, such as will enable others skilled in the art to which it appertains to make and use the same.

This invention relates to improvements in multiple needle sewing-machines, and it has more particular reference to a machine of this class wherein novel means is employed and associated with the needle-bars in such a manner that they may be operated simultaneously or independently, that is, both of the needle-bars may be operated at the same time to form a double row of stitching, or one of them may be made inoperative and only a single needle-bar permitted to operate when it is desired to form only a single row of stitching.

The object of this invention is to improve upon the construction for carrying out the above mentioned principles of operation, by the provision of a simply constructed device which is extremely inexpensive to manufacture, yet equally as efficient in use as more intricate and expensive devices for bringing about the same result.

Other objects and advantages of the invention will be apparent during the course of the following description.

In the accompanying drawings forming a part of this specification and in which like numerals are employed to designate like parts through the same:

Figure 1 is a sectional fragmentary view of a portion of a conventional type of machine-head, equipped with my improved mechanism, the needle-bars being shown connected together for simultaneous operation.

Fig. 2 is a view like Fig. 1, disclosing the relative position of the needle-bars when one of them is inoperative.

Fig. 3 is a section on the plane of the line 3—3 of Fig. 1.

In carrying out my invention I employ a drive-shaft which is associated with the needle-bars and is adapted to reciprocate the latter in the usual manner, said shaft including a crank-portion, which is com-

posed of disconnectible sections, each of which carries and actuates one of the needle-bars.

Referring to the drawings, the numeral 1 indicates a portion of a machine-head which may be of any suitable construction, being preferably formed in a manner similar to that shown. The numerals 2 and 3 indicate a pair of needle-bars, which are reciprocated through the action of a drive-shaft 4 which coacts with them. This drive-shaft includes a crank-portion 5, which consists of separable parts provided with crank-pins 6 and 7, the latter being carried by a rotatable member which is journaled in the head 1, while the former is supported in any suitable manner and rotated by suitable means. These crank-pins 6 and 7 are readily disconnectible, so that the crank-pin 6 which carries the needle-bar 3 may be operated independent of the crank-pin 7 which carries needle-bar 2, when it is desired to form a single line of stitching. These crank-pins are connected together for simultaneous operation by means of a member preferably in the form of a screw 8 which extends through the crank-pin 7 and has threaded engagement with a socket 9 formed in the crank-pin 6. The entrance to the threaded socket 9 is enlarged as indicated at 10 to permit the separable parts 6 and 7 to be more readily connected together. In other words, the socket 9 is enlarged at this point to permit the screw 8 to be more easily and readily engaged with said socket. Emphasis is to be laid on the fact that the screw 8 is of a length to permit it to extend into an opening 11 in the head 1 when the needle-bar 2 is inoperative. While I have shown and described an opening, in which the head of the screw 8 is received when the needle-bar 2 is out of use, I desire it to be understood that any other means may be employed for this purpose, such for instance, a shoulder may be provided with which the head of the screw may be engaged.

When it is desired to form a double row of stitching, the needle-bars will be connected together for operation in the manner disclosed in Fig. 1. If it is desired now to form a single row of stitching only, the needle-bar 2 may be quickly and easily put out of use. To accomplish this, the hand-wheel, by means of which the drive-shaft

4 is rotated, will be turned until the lower ends of both of the needle-bars are substantially even, or assume a position approximately like that shown in Fig. 1. 5 When in this position, a screw-driver may be inserted through the opening 11, and engaged with the kerf in the head of the screw 8. Now, by rotating this screw in the usual manner, the crank-pin 6 of the 10 shaft carrying the needle-bar 3 will be disconnected from the crank-pin 7, and the head of the screw will have moved in a position to project into the opening 11, which position will retain the needle-bar 15 2 in inoperative position, as disclosed in Fig. 2.

To connect the parts of the shaft together again for simultaneous operation of the 20 needle-bars, the hand-wheel may be rotated until the lower ends of the needle-bars are substantially even again, whereupon the 25 socket 9 will be in a position to receive the screw 8, and the parts may be then easily and quickly connected.

Where the machine is used for simultaneously producing a double line of stitching each of the needle-bars 2 and 3 will be provided with a needle and suitable thread 30 tensioning devices, and a pair of shuttles will, of course be arranged in the base of the machine to coact with the needles.

By the foregoing construction and arrangement of parts, it will be seen that either one or both of the needle-bars may 35 be operated. That is, when it is desired to form a single line of stitching only, a single bar may be operated, while if it is desired to form a double row of stitching both of the needle-bars may be placed into use.

In Fig. 3 I have shown one of the needle-bars, and the manner in which the drive-shaft coacts therewith to actuate it. This arrangement consists in forming the needle-bar with an enlarged portion 12 which is 40 provided with a transverse curved slot 13, through which the crank-portion 5 of the drive-shaft extends. This or any other suitable construction would equally well serve the purpose.

From the foregoing description taken in connection with the accompanying drawings, it is believed that the operation of my device is entirely obvious, and for this reason, further description is deemed unnecessary.

I claim:

1. In a multiple needle sewing machine, a support, a rotary shaft journaled therein, and provided at one end with a crank-pin,

a member rotatable in said support, its axis 60 of rotation being in alinement with that of the shaft and it being provided with a crank-pin adapted to aline with the first named crank pin, needle bars carried by said crank pins, and means also carried by 65 one of the crank-pins for coupling it with the other crank-pin to cause both needle bars to operate in unison or one of them alone.

2. In a multiple needle sewing machine, 70 a support, a rotary shaft journaled therein, being provided at one end with a crank-pin having a socket, a rotary member also carried by the support, being disposed in alinement with said shaft and being provided 75 with a bored crank-pin adapted to aline with the first crank-pin, a needle bar carried by each of the latter, and a connecting pin passing through the bore in one of the crank-pins, being receivable in the socket in the 80 remaining crank-pin, whereby the needle bars may be operated in unison or one of them alone.

3. The structure set forth in claim 2, there being a shoulder on the support on which 85 the connecting pin may rest when the crank-pins are disconnected.

4. A multiple needle sewing-machine comprising a casing having a shoulder therein, a drive-shaft in said casing, said shaft including a separable crank portion, a plurality of needle bars, one being associated with and operated by each section of the crank, and a removable connecting member carried by one section and engageable with 95 the other section, a portion of the member being engageable with said shoulder when the sections are disconnected.

5. A multiple needle sewing-machine comprising a casing having an opening therein, 100 a two-part crank-shaft in said casing, one part being journaled therein adjacent said opening, a needle-bar carried by each of the respective parts of the crank-shaft, one of said parts being provided with a horizontal screw-threaded hole extending therethrough, the other part having a screw-threaded socket to register with said hole, and a screw extending through said hole and into said socket to unite the parts to cause 110 simultaneous actuation of the needle-bars, said screw being operated through the opening in the casing and being of a length to extend into said opening when the parts of the crank-shaft are disconnected.

In testimony whereof I have hereunto set my hand and seal.

EDGAR C. MATSON. [I.S.]
